[57] CLAIM

The ornamental design for a combined hand exerciser and cigarette lighter, as shown and described.

DESCRIPTION

FIG. 1 is a perspective view of a combined hand exerciser and cigarette lighter showing my new design from the rear, right side and top;

FIG. 2 is a front elevational view thereof;

FIG. 3 is a rear elevational view thereof;

FIG. 4 is a right side elevational view thereof, the left side being a mirror image thereof;

FIG. 5 is a top plan view thereof; and,

FIG. 6 is a bottom plan view thereof.

FIG. 3FIG. 2FIG. 1FIG. 5FIG. 6FIG. 4
